UNITED STATES PATENT OFFICE.

GEORGE T. SOUTHGATE, OF NEW YORK, N. Y.

HIGH-POTENTIAL SWITCH.

1,417,420.

Specification of Letters Patent. Patented May 23, 1922.

Application filed April 26, 1920. Serial No. 376,748.

To all whom it may concern:

Be it known that I, GEORGE T. SOUTHGATE, a citizen of the United States, residing at New York, in the State of New York, have 5 invented certain new and useful Improvements in High-Potential Switches; and I do hereby declare the following to be a full, clear, and exact description of the invention, such as will enable others skilled in the 10 art to which it appertains to make and use the same.

My invention relates to high potential switches.

Among the objects of my invention are:

15 To provide certain improvements upon the structures shown in my U. S. Letters Patent #1310585 granted July 22, 1919, for high potential switches and among the improvements made thereupon are to be 20 noted:—

The use of conical spiral discharge horns in combination with vertically disposed masts.

25 The use of vertically disposed axially revoluble insulators for supporting the masts.

30 The use of a choke coil for damping high frequency oscillations in the line and so disposed that its electro-magnetic arc-repelling effect may be used to aid in extinguishing the arc when the contacts of my improved switch are separated.

35 The use of improved forms of roller contact to obviate the interference of sleet with the operation of same.

40 The use of a spring connected to the revoluble insulators so that the force due to said spring may be used for bringing the switch contacts together or to separate said contacts, as desired.

In carrying out my invention, I make use of the instrumentalities illustrated in the accompanying drawing, in which:

45 Fig. 1 is a side elevation of my improved switch.

Fig. 2 is a view of the parts shown in Fig. 1 looking in the direction of the arrow 2 in said figure. The rod 17 is omitted in this figure for the sake of clearness.

50 Fig. 3 is an enlarged side view of the rotary contacts.

Fig. 4 is a view of some of the parts shown in Fig. 3 looking in the direction of the arrow 4 in said figure.

Fig. 5 is a diagrammatic view of my preferred form of choke coil.

Fig. 6 is a detail view of the driving mechanism for my improved switch when viewed in the direction of the arrow 6 in Fig. 1.

In the drawings:—

10 represents insulators which are of any preferred form of construction and of which there may be any number assembled tandem vertically in order to suit the potential of 65 the current on the line which the switch is designed to break.

The lowermost of the insulators 10—10 are supported upon shafts 11—11 and the latter are revolubly mounted in brackets 70 12—12 which are secured to the frame 13, the latter being supported upon any approved structure, two of the members of which may be as shown at 21—21.

Bevel pinions 14—14 are secured upon the 75 lower ends of the shafts 11—11 and said pinions mesh with the bevel gears 15—15. The bevel gears 15—15 are secured upon the shafts 16—16 and the latter are revolubly mounted in suitable bearings provided in 80 the brackets 12.

A connecting rod 17 has each end pivotally connected as at 18 to one of the gears 15. A bevel pinion 19 meshes with one of the bevel gears 15 and said pinion is mounted upon 85 the shaft 20 which is revolubly mounted in a bearing provided in the frame 22, the latter being supported at its upper end upon the shaft 16 and having its lower end held fixed by the brace 23 secured thereto and 90 to the structure 21.

A collar 24 is secured upon the shaft 20 and said collar is provided with a socket for the reception of the hand lever 25. Said collar is also provided with a lug 26 having 95 a hole for the reception of the locking bolt 27. The locking bolt 27 passes through holes in the bracket 28 and is normally retained in place by the padlock 29. The bracket 28 is provided with bearings for the lower end 100 of the shaft 20 and said bracket is secured upon the structure 21.

The supports 30—30 of the lowermost insulator are provided with hooks 31—31 to each of which is secured one end of one of the springs 32—32, and the other ends of said springs are connected together by the rod 33.

According to the angular location of the hooks 31 upon the respective supports 30 depends whether the force of the springs 32 is applied to aid in the opening of the switch or whether it is applied to aid in the closing of the switch.

In the drawings, the hooks 31—31 are placed substantially in the plane passing through the axes of the shafts 11—11 and when thus placed the springs 32—32 will tend to keep the arms 34—34 in the positions shown in Figs. 1 and 2 and to restore them to these positions when moved therefrom. If the hooks 31 are placed on opposite sides of said plane, then the springs 32 will aid in moving the arms 34 either toward or away from the position shown in Figs. 1 and 2 according to the relative locations of said hooks to said plane.

Arms 34—34 are secured to each of the uppermost insulators in any approved manner and masts 35—35 are also secured to said insulators in axial alignment therewith. Near the top of each mast are insulators 36—36 which are provided for a purpose hereinafter explained, and horn supports 37—37 are secured on the upper ends of said insulators.

Springs 38 are secured to the inner ends of the arms 34 and on the upper spring on the left of Figures 1 and 3 is revolvably mounted the contact wheel 39. The contact wheel 40 is provided with a shaft 41 which extends through a hole which is provided in the wheel 39 and has its lower end revolvably mounted on the lower spring 38. In a similar manner, the lower and upper contact wheels 42 and 43 on the right of said figures are secured to the corresponding springs 38. The springs 38 on the left of said figures may be adjusted towards each other by the screw 44 so as to move the abutting faces of the wheels 39 and 40 further apart. Similarly, the springs 38 on the right of said figures may be adjusted away from each other by the screw 45 so as to move the outer faces of the wheels 42 and 43 closer together.

The peripheries of the wheels 39 and 40 are shaped to make a re-entrant angle with each other and the peripheries of the wheels 42 and 43 are shaped to make a salient angle with each other so that the latter may be readily introduced between the former, as hereinafter explained.

Discharge horns 46—46 are each supported at one end by the support 37 and extend downwardly in the form of a conical spiral to the braces 47—47 and from said

braces said horns extend in a curve horizontally as shown in Figures 1 and 2 in order to make wiping contact with each other as at 48—48 and from the extremities of said horizontal portions said horns extend downwardly and are joined to the arms 34 as at 49—49.

Flexible connections 50—50 are connected to the terminals 51—51 which are mounted upon the springs 38—38 and serve to connect said springs with the line terminals 53.

The operation of the device just described is as follows:—

The parts being in the positions shown in Figs. 1 and 2, that is, in the positions which close the circuit through the connections 50—50; if the operator desires to open the circuit, he unlocks the padlock 29 and removes the bolt 27. He then applies his hand to the hand lever 25 which may be fixed in the collar 24 or removable therefrom, as desired, and moves said lever in the direction to cause the arm 34 on the left of Fig. 2 to move in a clockwise direction and the arm 34 on the right thereof to move also in a clockwise direction. The movement of said arms will cause the wheels 39 and 40 to be separated from the wheels 42 and 43, thus terminating the flow of current through said wheels. The current then flows through the discharge horns 46—46 and as said horns separate, the horizontal portions thereof will separate and an arc will form between said portions which as said horns continue to revolve will be transferred to the conical spiral portion. The conical spiral portion is so shaped that the arc will be substantially in the plane passing through the masts 35—35 throughout the motion of said horns until said arc is broken. The insulators 36—36 are placed between the masts 35 and the supports 37 in order to prevent the current from traveling down said horns. The flow of current through the loops formed by flexible connections 50—50 and the discharge horns 46—46, in series tends to establish an electro-magnetic flux which acts as a magnetic blow-out to aid in the extinguishment of the arc.

In order to amplify this effect and also to provide a choke coil for damping the high frequency oscillations upon the transmission line, I employ the arrangement shown in Fig. 5 in which the same numerals refer to the same parts as in the other figures and the construction of said parts is the same as just described, excepting that the flexible connection 50 passes at 52 into the interior of the mast 35, then through the arm 34, then through the brace 47, then through the discharge horn 46, then down through the mast 35 and continues the just described course for as many turns as desired and the other end thereof is joined to the terminal 51.

In the operation of my improved switch,

the coil just described not only increases the magnetic blowout effect which was hereinbefore adverted to with reference to the flexible connections 50 and horns 46, but said coil 5 also acts as a choke coil to damp out the high frequency oscillations which may exist at times upon a transmission line or may be induced therein by a switching operation itself.

Thus, it will be seen that I provide a simple, cheap and effective high potential switch 10 which includes means for extinguishing the arc and means for damping oscillations and in which many changes may be made without departing from the spirit of my invention.

15 I claim:—

1. In an electric switch, the combination with a pair of arms, of a pair of contact wheels mounted on one end of each arm and located to mutually contact, springs for 20 pressing the wheels of one pair of wheels towards each other, a spring for pressing the wheels of the other pair of wheels away from each other, an axially revolute insulator supporting the other end of each arm, 25 and means for rotating said arms.

2. In an electric switch, the combination with a pair of arms, of a pair of contact wheels mounted on one end of each arm and located to mutually contact, the edges of 30 one pair of wheels forming a re-entrant angle with each other and the edges of the other pair of wheels forming a salient angle with each other, springs for pressing the wheels of one pair of wheels towards each 35 other, a spring for pressing the wheels of the other pair of wheels away from each other, an axially revolute insulator supporting the other end of each arm, and means for rotating said arms.

40 3. In an electric switch, the combination with a pair of arms, of a contact mounted on one end of each arm, revolute supports for the other ends of said arms having parallel axes, means for turning said supports, masts axially in line with said supports and discharge horns extending between each of said arms and the corresponding mast.

45 4. In an electric switch, the combination with a pair of arms, of a contact mounted on one end of each arm, revolute supports for the other ends of said arms having parallel axes, means for turning said supports, masts axially in line with said supports and discharge horns extending between each of said arms and the corresponding mast, said discharge horns having a conical spiral form.

5. In an electric switch, the combination with a pair of arms, of a contact mounted on 60 one end of each arm, revolute supports for the other ends of said arms having parallel axes, means for turning said supports, masts axially in line with said supports, discharge horns extending between 65 each of said arms and the corresponding

mast, and an insulator in each of said masts to prevent the current from traveling downwardly in the corresponding mast.

6. In an electric switch, the combination with a pair of contacts, of arms for supporting said contacts, a mast connected with each of said arms, a discharge horn extending between each contact and each of said masts, an electric circuit closed by said contacts, means for moving said contacts to 70 open said circuit, a coil in series with said circuit and moving with each of said arms and located to direct its magnetic flux to assist in the extinguishment of the arc when said contacts are separated. 80

7. In an electric switch, the combination with a pair of contacts, of arms for supporting said contacts, a mast connected with each of said arms, a discharge horn extending between each contact and each of said masts, an electric circuit closed by said contacts, means for moving said contacts to 85 open said circuit, a coil moving with each of said arms and located to direct its magnetic flux to assist in the extinguishment of 90 the arc when said contacts are separated, said coils being in series with said circuit whereby they also act as choking coils.

8. In an electric switch, the combination with a switch arm, of a spring secured thereto, a contact wheel having an axial perforation secured to the end of said spring, a second spring secured to said arm, and a second contact wheel having an axially disposed shaft extending through said perforation and secured to the end of said second spring. 100

9. In an electric switch, the combination with a switch arm, of a spring secured thereto, a contact wheel having an axial perforation secured to the end of said spring, a second spring secured to said arm, and a second contact wheel having an axially disposed shaft extending through said perforation and secured to the end of said second 105 spring, the edges of said wheels forming a re-entrant angle with each other and said springs tending to press said wheels together.

10. In an electric switch, the combination with a switch arm, of a spring secured thereto, a contact wheel having an axial perforation secured to the end of said spring, a second spring secured to said arm, a second contact wheel having an axially disposed shaft extending through said perforation and secured to the end of said second 110 spring and means for adjusting the mutual approach of said wheels. 115

11. In an electric switch, the combination with a switch arm, of a spring secured thereto, a contact wheel having an axial perforation secured to the end of said spring, a second spring secured to said arm, and a second contact wheel having an axially dis- 120 130

posed shaft extending through said perforation and secured to the end of said second spring, the edges of said wheels forming a salient angle with each other and said springs tending to separate said wheels.

12. In an electric switch, the combination with a switch arm, of a spring secured thereto, a contact wheel having an axial perforation secured to the end of said spring, a second spring secured to said arm, and a second contact wheel having an axially disposed shaft extending through said perforation and secured to the end of said second

spring; and means for adjusting the mutual separation of said wheels. 15

13. In an electric switch, the combination with a base, of an insulator axially revolvable thereupon, a contact and a mast supported by said insulator, a line terminal and a flexible connection encircling said mast and having one end connected to said terminal and the other end connected to said contact.

In testimony whereof, I affix my signature:

GEO. T. SOUTHGATE
